CLEANING MACHINE

Russell A. Hetzer, Cincinnati, Ohio, assignor to
The American Laundry Machinery Company,
Norwood, Ohio, a corporation of Ohio

Application March 4, 1938, Serial No. 193,887

18 Claims. (Cl. 34—2)

This invention relates to improved apparatus for cleaning, renovating and otherwise treating a large mass of small material particles adapted to be conveyed by an air stream. I have chosen to describe the same as embodied in a machine for treating feathers, it being understood that I may apply it to other purposes.

This invention relates to an improved type of machine for treating feathers or the like in a batch process wherein the feathers are loaded directly into a container, treated in that container and unloaded directly out of the container into a receiver, all without the passage of the feathers through a fan or blower or through tortuous conduits. I thus avoid breakage of the quills and preserve the life and resiliency of the feathers.

My improved apparatus comprises a container for the feathers to be treated and a blower or fan having air inlet and outlet between the blower and container and also atmospheric air inlet and outlet, together with suitable control dampers so that feathers may be sucked into the container through a loading door by a stream of air passing from the container to the fan and then to atmosphere; the feathers may be treated by a stream of air passing through the container and recirculated through the blower at least in part; and the feathers may be unloaded into a receiving tick or the like by utilizing the blower to build up air pressure in the container for blowing the feathers out into the tick. In such a device I provide automatic means for starting the sterilizing treatment upon closing of the loading door, including the automatic closing off of the container from the rest of the circulating system. I also provide automatic timing mechanism for controlling the sterilizing operation and for re-establishing the circuit for the air circulating or treating system. Other controls provide for the automatic closing off of a portion of the air circulating system so as to build up a pressure in the feather container at the time the unloading door or valve is opened. Other controls are provided for a simplified arrangement of the air circulating circuits so that a single control member will set the necessary valves for the various feather treating operations.

Other objects and advantages of my improved control system will be apparent from the accompanying drawings and specification wherein I have shown certain improved mechanisms for carrying out the various feather treating operations mentioned above. The essential features of my invention will be set forth in the claims.

In the drawings, Fig. 1 is a front elevation of a machine embodying my invention with a part broken away to more clearly show certain of the control mechanisms; Fig. 2 is a side elevation with certain parts broken away to show the internal construction; Fig. 3 is a rear elevation of the machine with the rear housing panel removed; Figs. 4 and 5 are sectional plan views taken on the lines 4—4 and 5—5, respectively, of Fig. 2; Fig. 6 is a detail sectional view taken on the line 6—6 of Fig. 4; Fig. 7 is a fragmental detail view of a portion of the operating mechanism taken on the line 7—7 of Fig. 2; Fig. 8 is an elevational view of the mechanism of Fig. 7 looking from the right; Fig. 9 is a view like Fig. 7 showing the parts in an operated position; Fig. 10 is an enlarged sectional view taken on the line 10—10 of Fig. 1; Fig. 11 is a fragmental plan view of a portion of the mechanism of Fig. 10 showing in full lines an operated position of the parts and in dot-dash lines the unoperated position of the parts corresponding to Fig. 10; Fig. 12 is a front elevation of the mechanism of Figs. 10 and 11 also showing in dot-dash lines the unoperated position of the parts; Fig. 13 is a diagram of certain electrical operating circuits; while Fig. 14 is a detail perspective view of one of the scraping members in the feather container.

While many of the features of my invention are applicable to a single feather treating container, I have chosen to illustrate my invention as embodied in a unitary machine comprising two containers located side by side and having certain operating and control parts in duplicate and certain other parts functioning for both of the containers. In such a unit a single operator may treat different batches of feathers in the two containers simultaneously and perform the various control operations necessary. I thus obtain an increase in the volume of feathers treated per unit of labor and also provide saving in the operating and control mechanism necessary for a plurality of containers.

In the accompanying description where the parts are duplicated for the two containers and their associated apparatus I will describe one set of apparatus only, utilizing the suffix *a*, it being understood that in every such case there is a duplicate part which will have the suffix *b*. Where a part is described without any suffix after the reference character it will be understood that such part functions for the treating apparatus as a whole.

Substantially all of the apparatus is housed

within a suitable casing 15 which is designed with the necessary structural framework and covered by sheet metal or the like so as to provide a pleasing appearance and to protect all the parts. Within this housing and at the forward end thereof I have mounted two feather treating compartments substantially cylindrical in shape placed side by side as shown at 16a and 16b, there being an air space between them at 17. These containers depart slightly from cylindrical form in that the rear wall extends tangentially downward and the bottom wall extends tangentially rearward, meeting at the lower rear portion where an opening 18a is closed or opened by the control valve Fa. Through this opening an air stream enters the container tangentially so as to create a maximum swirling of the feathers during a treating or unloading operation. The top wall of the container is open for the passage of air therethrough from the point 19a to the point 20a and this section is provided with a double wire screen 21a of coarse and fine wire mesh. In the front wall of the container is a door 22a for observation and access to the interior of the container. This door preferably has a glass window and is provided with slotted openings and thumb screws, together with suitable gaskets, so that the door may be secured in place with an airtight connection. Also at the front of each container is an unloading nozzle such as shown at 23a communicating with the opening 24a in the forward wall of the container. This opening is controlled by the valve or door Ha best seen in Fig. 10. Located centrally of the containers and passing through both of them is a shaft 25 which is journaled in the side walls of the housing or cabinet and provided at one end with the sprocket 26 which is drivingly connected by a chain 27 with a geared head motor 28. An idler sprocket 29 keeps the chain tight. Mounted on this shaft are three agitator arms 30a spaced 120° apart. Each arm carries at its end a scraper blade 31a spring pressed into engagement with the walls of the container by springs 32a. The blade 31a is preferably of Bakelite or similar composition which will not wear away the metal wall of the container. The container has an opening for loading feathers thereto as shown at 33a which is adapted to be closed by a door 34a which is rigidly secured to the shaft 35a which in turn is rotatably mounted in the brackets 36a. This shaft extends rearwardly for a control purpose later disclosed. The door has a gasket 37a and a latch 38a for holding it in closed position. At the loading door is a hopper 39a for receiving feathers as they are loaded into the container. This hopper has a false bottom screened at 40a through which heavy foreign particles may fall into the space below, which may be cleaned out by the door at 41a.

Air circulation is provided by a blower 42 suitably mounted in the lower rear portion of the casing and having a driving pulley connected by belts 43 with the pulley of a motor 44. This blower has two air outlets, one through conduit 45, heater 46 and conduit 47a leading to the container opening at 18a. Referring to Fig. 4 it will be noted that conduits 47a and 47b are separated by a partition 48. In conduit 45 is the control damper E. A second air outlet from the blower is best seen in Figs. 2, 3 and 4 and comprises the conduit 49 controlled by valve or damper D and extending rearwardly and upwardly to the atmospheric outlet 50 at the upper rear portion of the machine. The blower has an atmospheric 75 Fb. Fixed to one end of shaft 76 is arm 80

air inlet through conduit 51 which leads to a suitable screened or filtered inlet opening 52 in one of the side walls of the cabinet. Conduit 51 is controlled by a damper or valve C. A second air inlet for the blower communicates through filter means with the screened opening 21a at the top of the feather container. This second inlet comprises a conduit 53 branching off the conduit 51. This in turn communicates by conduits 54a and 54b with the filter units 55a and 55b. The filter in turn is connected by conduit means 56a with the screened opening 21a in the feather container. This conduit at the inlet to the filter is provided with the partition plates or vanes 57a for evenly distributing the air to the filter. The flow of air through conduit 56a to the filter is controlled by the valve or damper Aa which is normally held open by a spring 58a.

A suitable form of filter as shown at 55a comprises an inlet manifold 59a having a plurality of circular openings 60a each communicating with a tubular filter member 61a connected to similar flanged openings 62a in a bottom plate which forms a division wall for the dirt receiving section below the filters where a drawer 63a is provided. It will be understood that air enters the filter at 59a and passes through the plurality of tubular filter units into the space 64a which communicates with the conduit 54a leading to the blower. Air flow in conduit 54a is controlled by the valve Ba. The dirt collects inside the filter units 61a and falls into the drawer 63a which may be readily removed for cleaning. Doors 65a give access to the filter units 61a so that they may be tapped or shaken to loosen the dirt caught in them if necessary. The outer wall of the cabinet is provided with doors 66a giving access to the entire filtering apparatus. The filter has an atmospheric outlet at 67a in its lower rear wall and this communicates by a branch duct 68a with the atmospheric air outlet 49-50. The outlet conduit 68a is controlled by a valve or damper Ga.

Means is provided for introducing a sterilizing fluid into the feather container. This comprises a spray head 69a connected by pipe 70a with a source for sterilizer fluid, such as steam or the like. This pipe is controlled by the valve 71a which is provided with an actuator, such as a solenoid 72a. As will presently be described, means is provided for energizing the solenoid 72a coincidentally with the closing of door 34a and timing means is provided to time the operation of valve 71a.

In the above description I have enumerated air valves or control dampers A to H inclusive. I provide a simplified control means so that certain of these valves may be operated coincidentally for various control operations. During the feather loading operation valves A, B and D are open and valves C, E, F, G and H are closed. To change to a feather cleaning or treating operation it is necessary to open C, to close D and to open E and F. It is also advisable to at least partly close B and to at least partly open G. B and G may be respectively entirely closed and opened if desired. The control mechanism for accomplishing these valve movements is as follows: Located at the front of the machine is the manual 73. This is connected by rod 74 with arm 75 on cross shaft 76. The lower end of lever 75 is connected by a link 77 with arm 78 on a shaft 79 which extends transversely of the containers and supports both of the valves Fa and Fb. Fixed to one end of shaft 76 is arm 80

which is connected by a link 81 with arm 82 of shaft 83. This shaft carries arms 84a and 84b which are connected by links 85a and 85b with arms 86a and 86b which operate valves Ba and Bb respectively. An arm 87 on shaft 83 is connected by link 88 with an arm 89 on shaft 90. Valve E is operated directly from shaft 90. Shaft 90 also carries an arm 91 which is connected by link 92 with valve D. Another arm 93 on shaft 90 is connected by link 94 with valve C. An arm 95 on shaft 90 is connected by link 96 with arm 97 on shaft 98. This shaft carries two arms 99a and 99b which are connected by links 100a and 100b with valves Ga and Gb respectively. The arrangement of all of these valves and connecting parts is such that with manual 73 in its rearward position, valves B are open, valve C is closed, valve D is open and valves E, F and G are closed. With the manual 73 in its forward or operated position the valves B are at least partly closed, valve C is open, valve D is closed, valves E and F are open and the valves G are at least partly open.

Means is provided after feathers have been placed in a container through the loading door 34a for automatically starting the sterilizer spray 69a by opening valve 71a and at the same time for closing valve Aa upon closing of the loading door. Referring to Figs. 7, 8 and 9, shaft 35a which is oscillated by opening and closing of door 34a extends rearwardly and is rigidly attached to a tubular member 101a. Reciprocably mounted in the tubular member is the rod 102a which carries at its forward end a roller 103a. This rod is biased toward extended position by a spring 104a. The endwise movement of rod 102a relative to 101a is guided and limited by a pin 105a connected to 102a which engages in a slotted plate 106a which is attached to 101a. Mounted on 101a is a mercury switch 107a for controlling electrical circuits later described. The roller 103a engages in a slot or recess in a member 108a which is mounted for vertical movement in a bracket 109a. The upper end of member 108a is connected by cable 110a with valve Aa. This cable passes over suitable guiding pulleys 111a. When door 34a is open the parts are in the full line position of Fig. 7. When door 34a is closed the parts move to the dot-dash position of Fig. 7 closing the contacts of the mercury switch 107a to start action of the sterilizer spray and action of a timing device as will be later described at the same time the member 108a is moved downwardly to close valve Aa. The parts remain in the dot-dash position of Fig. 7 until completion of the sterilizing operation and the operation of the timing device which results in energization of solenoid 115a which is operatively connected to bellcrank 116a, one arm of which engages a pin 117a on rod 102a. The bellcrank is normally biased in clockwise direction by spring 118a and when the solenoid 115a is energized the bellcrank moves in a counterclockwise direction as shown in Fig. 9 withdrawing the roller 103a from the slot in 108a which permits valve Aa to open under the influence of its spring. The parts then remain in the full line position of Fig. 9 until the loading door is again opened when the parts return to the dot-dash position of Fig. 9 or the full line position of Fig. 7, whereupon the roller 103a again automatically engages in the slot of the member 108a.

Means is provided for preventing the movement of manual 73 forward for a feather treating operation when the loading door 34 is open. This

means comprises the member 119a fixed on shaft 76 in such a manner that it strikes 101a when the parts are in the full line position of Fig. 7 if it is attempted to pull manual 73 forwardly.

5 Means is also provided for preventing the opening of loading door 34a if the manual 73 is in its forward position. This is also a function of the member 119a which in the full line position of the parts in Fig. 9 rests beneath 101a in a manner to prevent opening of door 34a.

Means is provided to close the valves Aa and Ab to build up pressure in the containers at the time an unloading operation takes place, at which time the valves H are opened. This mechanism might be independent of other mechanism but in the present instance is connected to the member 108a already described in connection with Figs. 7, 8 and 9. The lower end of member 108a is connected by cable 112a with mechanism for operating valve Ha. As best seen in Fig. 2 valve Ha is controlled by handle 113a and this handle is connected with the cable 112a which passes over the guiding pulleys 114a. As best seen in Fig. 1, the handle 113a is equipped with a well-known mechanism for holding it in either of its two positions. This construction comprises a button on the end of the handle connected with a trigger which engages in a suitable slot in a bracket to hold the handle in either valve-closed or valve-open position.

25 Electrical control circuits including the circuits for automatically starting the sterilizer spray when the loading door is closed, for stopping the sterilizer spray after a predetermined time, and for restoring valve Aa or Ab to open position after a sterilizing operation are shown in Fig. 13.

30 A three-phase source of power is shown at L₁, L₂, L₃. Switch 135 energizes blower motor 44 and switch 136 energizes agitator motor 28. Suitable circuits connect the container illuminating lights 141a and 141b through snap switch 137. Other circuits connect the clock timers 138a and 138b and their respective signal lights 139a and 139b.

35 The automatic controls for containers 16a and 16b are shown at 142a and 142b respectively. These are exactly alike so one only is shown in detail and described.

40 One terminal of mercury switch 107a is connected to L₁ by line 143a. When loading door 34a is closed and switch 107a is closed, a circuit is completed through line 144a, terminal 145a, lines 146a, 147a, 148a and 149a, heater 150a, line 151a, normally closed switch 152a of relay R₁, and lines 153a, 154a, 155a, 156, and 157 to L₃.

45 Simultaneously a circuit is established from terminal 145a through line 158a, coil of relay R₂, line 159a, normally closed switch 160a of relay R₃, lines 161a, 155a, 156 and 157 to L₃. This circuit energizes relay R₂ closing normally open switch 162a which establishes a circuit from terminal 145a through lines 163a and 164a, solenoid 72a, lines 156 and 157 to L₃. Energization of solenoid 72a opens valve 71a admitting steam through spray 69a.

50 The above circuits are established simultaneously and the heater 150a begins to heat the thermostatic timer switch 165a simultaneously with the opening of valve 71a. After a predetermined period which, for example, in this case is 15 seconds, the contact X of switch 165a moves from terminal Y into contact with terminal Z thereby establishing a circuit from terminal 145a through lines 146a, 147a, 166a, relay coil R₁, lines 167a and 168a, terminals X and Z of 165a, lines 169a,

154a, 155a, 156 and 157 of L₄. This circuit energizes coil R₁ opening switch 152a and closing switch 170a. Closing 170a establishes a circuit from terminal 145a through lines 146a, 147a, 168a, coil R₁, line 167a, switch 170a, lines 171a, 154a, 155a, 156 and 157 to L₃. This is a maintaining circuit for coil R₁ and maintains switch 170a closed and 152a open. Opening 152a breaks the circuit to heater 150a and, when 165a cools, its terminal X makes contact with terminal Y and breaks contact with terminal Z. This requires a period of time which, for example, is 15 seconds. When terminals X and Y are reconnected a circuit is established from terminal 145a through lines 146a, 147a, 148a, coil R₃, 172a, 173a, 174a, terminals Y and X, line 168a, switch 170a, lines 171a, 154a, 155a, 156 and 157 to L₃. This energizes relay R₃ opening switch 180a and closing switch 175a. Opening 180a breaks the circuit through the coil of relay R₂ which opens switch 162a in turn breaking the circuit to solenoid 12a. Deenergization of this solenoid causes steam valve 71a to close (under influence of a spring not shown) and the sterilizing steam spray operation, which has now been in operation 30 seconds, is completed. The closing of switch 175a establishes a circuit from terminal 145a through lines 146a, 147a, 148a, coil R₃, lines 172a, 173a, switch 175a, lines 176a, 155a, 156 and 157 to L₃. This is a maintaining circuit for coil R₃ and maintains switch 175a closed and switch 180a open. A circuit is also established from terminal 145a through lines 146a, 177a, coil of relay R₄, lines 178a, 173a, switch 178a, lines 185a, 156 and 157 to L₃. This energizes coil of relay R₄ and closes switch 179a which establishes a circuit from terminal 145a through line 148a, switch 178a, line 180a, solenoid 115a and line 157 to L₃. Energization of this solenoid rotates bellcrank 118a (see Figs. 7 and 9) releasing roller 103a from the slot in member 108a permitting spring 58a to return valve Aa to open position.

If it is desired to operate the steam spray valve at other times during operation of the machine it may be accomplished by manually operated switch 140a. Closing this normally open switch establishes a circuit from L₁ through 181a directly to the coil of solenoid 12a and thence to L₃.

The means provided for securing a feather receiving tick or the like to the unloading nozzles 23a is best seen in Figs. 1, 2, 10, 11 and 12. Through a pair of coil springs 120a and 121a is threaded a cable 122a. One end of the cable is connected to a lever arm 123a which is pivotally mounted on a pin 124a supported in a suitable bracket. A spring 125a is connected between the pin and the lever arm in a manner to bias the lever outwardly to the dash-dot position of Fig. 11. A lever arm 126a similar to 123a is mounted in the same manner on the other side of the unloading nozzle. Cable 122a extends around the lower half of the nozzle through spring 121a and is threaded through a hole in lever arm 126a, then continues around the upper half of the nozzle through spring 120a and through a second hole in lever arm 123a, then downwardly around pulleys 127a where its lower end is connected to the arm of a lever 128a. This lever is fixed to a shaft 129a supported in a bracket 130a. A pedal 131a is also fixed to shaft 129a and has pivotally connected at its inner end a weighted latch member 132a. A trip lever 133a is rotatably mounted on shaft 129a. When pedal 131a is depressed the latch 132a rotates under the influence of the

counterweight and engages on top of the ledge 130a of the bracket. The ends of the coil spring 121a engage the lower faces of lever arms 123a and 126a. The ends of spring 120a likewise engage the upper faces of levers 123a and 126a.

The parts just described normally occupy the position shown in Figs. 1, 2 and 10 and also shown in broken lines in Figs. 11 and 12. To secure a tick on the unloading nozzle 23a the tick is placed over the nozzle beneath the springs and in contact with a resilient insert 134a of cork or the like which surrounds the nozzle beneath the springs. Pedal 131a is then depressed which rotates the lever 128a clockwise, thus pulling the cable 122a and tightening the coil springs 120a and 121a around the unloading nozzle. This moves the lever arms 123a and 126a inwardly to the full line position of Fig. 11. The latch 132a engages the ledge on the bracket and holds the parts in this position. The insert 134a provides a close contact between the tick and the nozzle and increases the friction maintaining the tick in position. Metal to metal contact at this point might cut the fabric of the tick. To release the mechanism the trip lever 133a is depressed releasing the latch and permitting the mechanism to return to the original position of Fig. 10, relieving the clamping effect on the tick and permitting springs 120a and 121a to expand to open position.

Operation

In the idle position of the machine it will be assumed that the blower motor 44 and the agitator arm motor 28 are shut down; that the manual 73 is in the unoperated or rearward position of Fig. 2; that levers 113a and 114b are in the position of Fig. 2 corresponding to closed position of valves Ha and Hb; and that loading doors 34a and 34b are in the open position in which case the rollers 103a and 103b are engaged in the slots of members 108a and 108b and in the full line position of Fig. 7. The operator then closes switches 135 and 136 starting the blower motor and the agitator motor. Next she may, if desired, illuminate the interior of the compartments by operating the snap switch 137 on the front control panel.

The next operation is the loading of a batch of feathers. With the parts in the position just described, air enters each container, the circuit for container 16a being as follows: Through loading door 34a, screens 21a, conduit 66a, valve Aa, filter 55a, duct 54a past valve Ba, into conduits 53 and 51 to the suction side of the blower, then through the blower and conduits 48 and 49 to atmosphere, passing valve D which is open. This creates a suction through the loading doors so that as feathers are dumped from a bag or other container into the hopper 38a they will be drawn into the treating compartment 16a. When this compartment is completely loaded, door 34a is closed and the operator moves to the other side of the apparatus, loading another batch of feathers into compartment 16b.

Closing door 34a rotates rod 35a and moves the member 101a and associated parts to the dot-dash line position of Fig. 7. This closes valve Aa through the connecting cable 110a and at the same time closes the contacts of the mercury switch 107a. This results in energization of solenoid 12a which opens valve 71a, admitting steam or other sterilizing fluid into the container 16a. The same operation takes place in the other compartment after its loading door

has been closed. This operation in both containers is automatically timed say for a period of thirty seconds, at the end of which time the spray is automatically cut off and the valves A_a and A_b are automatically returned to open position in the manner already described.

Upon closing the door $34b$ the operator moves to the front of the machine and pulls forwardly on manual 13 . This moves the interlocked members $119a$ and $119b$ into position preventing opening of the doors $34a$ and $34b$. At the same time it opens valve C , closes valve D , opens valves E , F_a and F_b . It also moves valves B_a , B_b , G_a and G_b to half-way open position. If desired, valves B may be entirely closed and valves G entirely open so that no air is recirculated. The path of the air is now from the blower through conduit 45 , heater 46 , conduits $47a$ and b , into the containers $16a$ and $16b$ producing a swirling movement of the feathers therein in addition to the constant agitation produced by the rotating arms $30a$ and $30b$. Following the air from compartment $16a$, it passes through screens $21a$, conduit $56a$, filter $55a$ from which part of the air is exhausted through the outlet $67a$ and the atmospheric conduit $68a$, the other part passing through the partly open valve B_a and through conduits $54a$, 53 and 51 back to the blower. The necessary make-up air enters the blower through the fresh air intake conduit 51 as valve C is open. The clock timers $138a$ and $138b$ may be set to energize the signal lights $139a$ and $139b$ at the end of this operation.

When these signal lamps are illuminated it is time for the unloading operation. Manual 13 is left in its operated position and assuming that ticks have already been placed on the unloading nozzles $23a$ and $23b$, the handles $113a$ and $113b$ are moved to open the valves H_a and H_b and to close valves A_a and A_b . The air circuit is now through conduit 51 into the blower and out through conduits 45 and $47a$ into the compartment $16a$ and out through the nozzle $23a$ carrying the feathers into the tick. Just at the finish of this operation the hand switches $140a$ and $140b$ (see Fig. 13) are momentarily depressed, injecting a shot of steam into the compartment, breaking up static electricity and avoiding any tendency of the feathers to stick to the container walls.

This is a complete cycle and may be immediately repeated in which case the handles $113a$ and $113b$ are returned to their former position and manual 13 is moved rearwardly. The loading doors may then be opened.

It is not necessary to wait until the sterilizing operation in compartment $16b$ is completed before moving the operating manual 13 forwardly to the treating position. In other words this can be done immediately after closing the loading door $34b$, thus starting the treating operation in compartment $16a$ because valve A_b remains closed until the sterilizing operation is completed in container $16b$ after which it is automatically opened and the treating operation will commence.

It is possible also to load one of the containers while the treating operation is being performed in the other compartment by moving manual 13 rearwardly for the period of time required to load the container. This of course interrupts the cleaning and drying or treating operation in the other container but it is only for the few seconds required for a loading operation.

It is also possible to unload one container while a treating operation is going on in the other.

This is accomplished by moving the handle $113a$ or $113b$ of the container to be unloaded which will close the respective valve A and open the respective valve H .

5. What I claim is:

1. In apparatus of the class described, a container for material to be treated, there being an opening through a wall of said container, a door for closing said opening, there being a second opening through a wall of said container and air circulating means communicating therewith, means for sterilizing material in said container, a timing device, means for simultaneously closing said second named opening and starting said sterilizing means and starting said timing device, and said device having operative connections on the one hand with said closing means for causing opening of the latter and on the other hand with said sterilizing means for stopping the latter after a predetermined time interval.

2. In apparatus of the class described, a container for material to be treated, there being air inlet and outlet openings in said container, air circulating means for moving air into said container through one of said openings, said circulating means also being arranged to move air out of said container through one of said openings, valve means for segregating said container from said air circulating means including a valve having open and closed positions, aperture means for unloading material from said container, a door for closing said aperture means, means for sterilizing material in said container, control means for said valve including interengaging parts, one part having an operative connection with said sterilizing means, the other part having an operative connection with said valve, means for moving said parts together to cause operation of said sterilizer means and closing of said valve, means for disengaging said parts to permit said valve to open, and means for closing said valve by said door in closing.

3. In apparatus of the class described, a container for material to be treated, there being an opening through a wall of said container for introduction of material, a door for closing said opening, means for sterilizing material in said container, electrical means for causing operation of said sterilizing means and including an electric circuit and a switch, and a rod operatively connected with said door and said switch for closing the latter by said door in closing.

4. In apparatus of the class described, a container for material to be treated, there being an opening through a wall of said container, a closure for said opening, a blower, air inlet means for said blower comprising conduit means communicating with said container, a screen across said conduit means at the container end thereof, filter means in said conduit means, an atmospheric outlet from said filter means, a valve in said outlet, air outlet means from said blower to atmosphere, a valve in said air outlet means, a conduit connecting said blower outlet with said container, a valve in said conduit, a heater in said conduit, and a single control means for at least partially opening said first named valve and for closing said second named valve and for opening said third named valve.

5. In apparatus of the class described, a container for material to be treated, there being an opening through a wall of said container, a closure for said opening, a blower, air inlet means for said blower comprising conduit means communicating with said container, a screen across

said conduit means at the container end thereof, filter means in said conduit means, a valve in said conduit means between said filter means and blower inlet, an atmospheric outlet from said filter means, a valve in said outlet, air outlet means from said blower to atmosphere, a valve in said air outlet means, a conduit connecting said blower outlet with said container, a valve in said conduit, a heater in said conduit, and a single control means for partially closing said first named valve and at least partially opening said second named valve and for closing said third named valve and for opening said fourth named valve.

6. In apparatus of the class described, a container for material to be treated, there being an opening through a wall of said container, a closure for said opening, a blower, air inlet means for said blower comprising conduit means communicating with said container, a screen across said conduit means at the container end thereof, air outlet means from said blower to atmosphere, a valve in said air outlet means, a conduit connecting said blower outlet with said container, a valve in said conduit, an atmospheric air inlet for said blower, a valve in said air inlet, and a single control means for closing said first named valve and for opening said second named valve and for at least partially opening said third named valve.

7. In apparatus of the class described, a container for material to be treated, there being an opening through a wall of said container, a closure for said opening, a blower, air inlet means for said blower comprising conduit means communicating with said container, a screen across said conduit means at the container end thereof, a valve in said conduit means between said container and blower inlet, air outlet means from said blower to atmosphere, a valve in said air outlet means, a conduit connecting said blower outlet with said container, a valve in said conduit, an atmospheric air inlet for said blower, a valve in said air inlet, and a single control means for partially closing said first named valve and for closing said second named valve and for opening said third named valve and for at least partially opening said fourth named valve.

8. In apparatus of the class described, a container for material to be treated, there being a material discharge opening through a wall of said container, a closure for said opening, a blower, air inlet means for said blower including a conduit communicating with said container, a screen across said conduit at the container end thereof, a valve in said conduit adapted to close it, other air inlet means for said blower, air outlet means from said blower to said container, and a single control means for closing said valve and opening said closure.

9. In apparatus of the class described, a container for material to be treated, there being an opening through a wall of said container, a blower, air inlet means for said blower comprising conduit means communicating with said container, a screen across said conduit means at the container end thereof, a valve in said conduit means, air outlet means from said blower to atmosphere, a valve in said outlet means, a conduit connecting said blower outlet with said container, a valve in said conduit, and a single control means for opening said first and second named valves and for closing said third named valve.

10. In apparatus of the class described, a container for material to be treated, there being an

opening through a wall of said container, a closure for said opening, a blower, air inlet means for said blower comprising conduit means communicating with said container, a screen across said conduit means at the container end thereof, filter means in said conduit means between said filter means and blower inlet, an atmospheric outlet from said filter means, a valve in said outlet, atmospheric air inlet means for said blower, a valve in said inlet, air outlet means from said blower to atmosphere, a valve in said air outlet means, a conduit connecting said blower outlet with said container, a valve in said conduit, a heater in said conduit, and a single control means for partially closing said first named valve and at least partially opening said second and third named valves and for closing said fourth named valve and for opening said fifth named valve.

11. In apparatus of the class described, a plurality of separate containers for material to be treated, there being an opening through a wall of each container, a door for closing said opening, there being a second opening through a wall of each container and common air circulating means having suction connections with all of said second openings, whereby with suction at said second opening and with the door for said first named opening in open position material may be loaded into said container, sterilizing means for each container, and means for selectively closing each of said second named openings and for coincidentally operating its associated sterilizing means.

12. In apparatus of the class described, a container for material to be treated, a door in a wall of said container for intake of material thereto, a blower, an air intake conduit for said blower communicating with said container, an air discharge conduit for said blower, a valve in said intake conduit normally biased toward open position, an actuator for closing said valve, an arm operatively connected with said actuator and with said door for closing said valve by said door in closing, switch means operable in switch-closing direction by said arm as said door closes, material treating means associated with said container, control means for said treating means, electrical means for causing operation of said control means and energized by closing of said switch means, and means for releasing the operative connection between said arm and said actuator operable by said electrical means.

13. In apparatus of the class described, a container for material to be treated, there being an opening through a wall of said container, a door for closing said opening, material treating means, conduit means for a material processing current communicating with said container, timing means, means operable by said door in closing for closing said conduit means and for starting operation of said treating means and for starting said timing means, and means operable by said timing means for stopping operation of said treating means a predetermined time after starting thereof.

14. In feather treating apparatus of the class described, a container for material to be treated, there being an opening through a wall of said container for introduction of material, a door mounted on said container for closing said opening, means for sterilizing material in said container, means for operating said sterilizing means, and an operative connection independent of ma-

terial introduced through said door between said last named means and said door for moving said last named means to operate said sterilizing means by said door in closing.

15. In apparatus of the class described, a container for material to be treated, a door in a wall of said container for intake of material thereinto, a blower, an air intake conduit for said blower communicating with said container, an air discharge conduit for said blower, a valve in said intake conduit normally biased toward open position, an actuator for closing said valve, means providing an operative connection with said actuator and with said door for closing said valve by said door in closing, timing means started by 15 said door in closing, material treating means associated with said container, and means for releasing said operative connection between said actuator and said door by operation of said timing means.

16. The combination of claim 15 wherein the parts are so arranged as to reestablish said operative connection between said actuator and said door by said door in opening.

17. In feather treating apparatus, a plurality of containers for feathers to be treated, there being an opening through a wall of each container and common air circulating means having a plurality of suction conduits communicating

one with each container and therethrough with each opening, whereby suction in said conduits will load material into said containers through said openings, a door for closing each opening, a 5 normally open valve in each conduit, feather sterilizing means for each container, actuating means for each sterilizing means, an operative connection between each door and its associated sterilizer actuating means for operating said actuating means, and means actuated by each of said doors for closing each of said valves as the door is closed.

18. In feather treating apparatus, a plurality of separate containers for feathers to be treated, there being an opening through a wall of each container, a blower, conduits, one for each container, communicating with the suction side of said blower and each communicating with its associated container and therethrough with one of 20 said openings, whereby suction in said conduits will load material into said containers through said openings, a screen in each conduit at the container end thereof, feather sterilizing means for each container, means for closing each opening, means for operating its associated sterilizing means, and control means interconnecting said two last named means for actuating them coincidentally.

RUSSELL A. HETZER.
